ABSTRACT

A snap action switch for alternating and direct current, improved by a solid support for the movable contact means in combination with a substantial distance between the stationary contacts. For longer life a robust spring mechanism is insulated against gas, arising from the arc.

10 Claims, 5 Drawing Figures

Conan H. Spaderna

SNAP ACTION ELECTRIC SWITCH

Generally snap switches have a spring mechanism enclosed in the arc chamber and thus exposed to the hot gases of the electric arc, which leads to earlier breakage than necessary. Its enclosure in the arc chamber restricts the size of the spring mechanism and hence the stored energy, available for the snap movement of the movable contact. As the snap energy is small, the movable contact has to be light and therefore breaks easily.

To overcome these drawbacks, the invention uses springs outside an insulating housing base, which thus shields the springs from heat and gases of the arc. A housing top above the housing base has a slot for the actuating lever to stick out. The housing base is shaped with a cylindrical cavity, to receive an insulating wheel. This wheel is substantially concentric with the cylindrical upper face of the housing base and is adapted to rotate in the housing, when turned by the lever, e.g. by a transverse shaft, pivoted in the housing top.

At least one pair of stationary contacts projects from the cylindrical base face. One or more movable contact means are so attached to the wheel that contact can be made across neighboring stationary contacts by turning the wheel. One or more spring mechanisms of the dead center type are attached outside of the housing base with their fixed ends to the housing top and with their center to an eccentric trunnion of the wheel. Stops are provided for halting the wheel rotation in closed or open positions of the switch.

The invention is shown in the drawing. However, it is to be understood that this invention is not limited to the details shown, but may embody modifications within its scope. In the drawing:

FIG. 1 is an end view of a switch embodying this invention;

FIG. 2 is a side view of the section on line A-A-A-A-A-A through FIG.1, looking from the right of FIG.1;

FIG. 3 is a bottom view thereof, seen from below of FIG.2;

FIG. 4 is an end view of a modified element in a section, marked by line C-C of FIG.5, seen from left of FIG.5, and

FIG. 5 is a side view thereof in a section on line B-B, seen from the right of FIG.4.

In the switch shown in FIGS. 1,2 and 3, a housing top 1 has brackets 11 and 12, formed in one piece with an oblong metal strap 15. This strap is pierced by holes 13 for screw attachment to a wall box, not shown, and tapped holes 14 for screw fastening of a not shown conventional lid; with household equipment on rollers a nook can house the switch. Fastened to the housing top is a housing base 2, made of plastic, e.g. Nylon. It comprises in the present embodiment two upright posts 16 that make easier the assembly of housing base and top, after the wheel 3 has been mounted. Small knobs 17 on the posts snap into opposite holes of the brackets 11 and 12.

A protective casing 18 of fiber or metal may be slipped over the whole length of the housing base tightly like a sheath, but it is open on top, except for narrow retaining ledges 19. For floor polishers, vacuum cleaners etc. the metal strap 15 may have different shapes, such as a ring segment to be screwed unto a round handle, while the switch rests inside the cut open handle.

In FIGS. 1,2, and 3 two movable contacts 21 and 22 can open or close circuits across stationary contact bars S₁, S₂, S₃ and S₄, resting inserted in the housing base 2. The stationary contacts end in eight terminals with running numbers 23 – 30, each having a suitable binding screw 32. In FIG. 2 the movable contacts are in positions 21 and 22 when the lever 31 takes its right hand position 31'. The same contact means hold positions 21' and 22' when the left hand position 31' of the lever, shown in dash-dot lines, is reached. The movable contacts are well embedded in the wheel 3, which is shaped for this purpose with a peripheral groove 33 and insertion niches 34. The wheel center is pivoted and secured by its metal shaft 35. This may be also achieved by two plastic trunnions, molded unto the wheel in its center. The wheel itself may be made of plastic or fiber; it is pivoted in and guided between the brackets 11 and 12.

The spring mechanisms are: 36 on the left hand side of FIG.1 and 37 on the right hand side. To avoid crowding of the drawing with lines, mechanism 37 is shown by the spring symbol, a rectangular with diagonals, which symbol is also used on one side of FIG.3 and on the two sides of FIGS.4 and 5. Each spring mechanism has two springs: 36 has the springs 38 and 38', while 37 has the springs 39 and 39'. These springs are hooked at one end to lugs 44 of the metal strap 15, at their other end to an eccentric trunnion 40 of the wheel 3.

If the wheel is turned by putting the lever 31 from one end of a strap slot 41 in FIG.2 to the other slot end, the trunnion 40 describes a bow 42. This bow path has to be above the upper contour 43 of the housing base 2, as free movement of the trunnions must be insured.

It can be best seen in FIG.2 how the switch operates. If lever 31 is thrown from its position 31'' into position 31', the trunnion 40 swings in its bow path 42 through dead center to a position 40'. The heavy pull, formerly exerted by the spring 38', is now coming from the elongated spring 38, while the spring 38' is relaxed. Thus two stable positions of the switch exist, which are defined as well as by the places where the lever rests, as by the extreme locations of the trunnion. If the lever is taking its position 31'', then the movable contact 22 is not touching any stationary contact and, being embedded in the groove 33, (FIG.1) it cannot touch any metal at all. At the same time the movable contact bridges the stationary contact bars S₂ and S₄. If the lever stays at 31', one movable contact holds an off-position 21', while the other makes contact between the stationary contact bars S₁ and S₃.

In FIGS. 4 and 5 all parts carry the same characters as their corresponding parts in FIGS. 1 – 3, yet, the number of movable contact means is raised to three (FIG.5); the number of stationary contact bars stays four, but each bar has only one terminal (FIG.4). Chosen positions 51 – 57 of the movable contacts are marked by arrows on the wheel rim in FIG.5. Although three movable contacts 52, 54 and 56 are shown here, one or two may be left out, if not needed. With lever 31 upright, only the circuit of the stationary contacts 29 and 30 is closed. The wheel 3 is temporarily locked in that position by a spring - loaded bolt 58, seated deep in the wheel 3 and reaching into a shallow hole, made for this purpose in the bracket 12. By pushing further the level 31, one can overcome this stop. At 59 and 60, more holes provide stops for further locations of lever 31; the stop 60 will halt the wheel after a short, clockwise travel in such a manner that the movable contact, formerly in position 52, will reach the location 51, which is all around insulated. The center contact travels from 54 to 53, closing a circuit between S₁ and S₃, after opening a circuit between S₁ and S₂. Meanwhile, the contact from position 56 bridges the contacts S₂ and S₄.

Readily, the same location of the movable contacts and of the stops 58 – 60 can be applied to the switch of FIGS. 1 – 3. It follows that a switch can be made for a variety of circuits, whose handling otherwise would require several switches. One movable contact in the center, or two or more movable contacts may be employed, using the same housing top and base, as well as the same spring mechanisms. This rich versatility is a new and desirable feature of the present invention, as the same tools can be used to make a variety of switches.

The second embodiment of the invention features some structural difference against the first one. The upright posts 16 of the housing base 2 are replaced in FIG.5 by two metallic end walls 16' of the housing top 1'- casing 18' assembly. As shown in FIG.4, the casing is slightly offset at the height 43 of the plastic housing base 2', to hold the latter firmly in place. Because the base 2' is smaller than the base 2, the former is less expensive to mold. However, the assembly requires ears 61 on top of the end walls 61', which ears are screwed to the strap 15 by screws 62, after the wheel 3 has been set in its place. Two leaf springs 63 are fastened to the end walls 16', to press downward on the wheel top with their roughened underside; thus those springs brake the snap momentum just before it reaches a stop, such as one end of the slot 41 in FIG. 5. The

wheel is made slimmer in its top section, see 31 in FIG.2, as it has to pass through the strap slot. Therefore stronger braking takes place when the wheel is turning up its broader part under the leaf springs 63, shown on the far side in FIG.4. By that frictional braking sudden vibration and harsh impact with the stop are kept away from the wheel.

The snapwheel switch, as described, is useful for small electric motors in altering the sense of turning by reversing one A.C. phase, or in speed changes by switching to a different combination of field coils. Both methods are known, but the invention offers possibilities of higher voltage and wattage, as the movable contact will stop often beyond the stationary contacts, opposite cooler housing parts. There the hot, ionized air cools and de-ionizes, forestalling restrikes of the arc.

This feature prolongates the life of the switch in other applications, too, even where only small currents are being switched.

In FIG.2 a jumper 64, of the same metal as all the contacts, ties the terminals 23 and 25; by this means the switch may be converted into a two-way switch. Either the first circuit is closed by the movable contact 21, or the other circuit may be closed by the movable contact 22 in its location 22'. The switch, shown here, has eight terminals, while the conventional two-way switches offer only two terminals for loads, and one for the source. For this reason they were misnamed "threeway" switches.

In FIG.5 one or both spring mechanisms might be arranged upside down with the trunnion 40' between the center 35 and top 31 of the wheel, and lugs 44' disposed on the endwalls 16' of the housing top 1'. Yet, commonly a trunnion 40 is seated in the area between the bottom 54 and wheelcenter.

I claim:

1. In an electric switch for snap action, a housing having a top provided with a slot, further having an insulating housing base shaped with an inner cylindrical face; at least two spaced stationary electric contacts projecting from the cylindrical face of the housing base; an insulating wheel substantially concentric with said cylindrical face and being disposed for rotation in the housing and provided with an actuating lever projecting through the slot; at least one movable contact means

carried by the wheel for movement by it across the stationary contacts; at least one spring mechanism disposed outside the housing base with a center and ends whereof the ends are fastened to the housing top and the center is attached eccentrically to the wheel; and stops provided for the wheel to halt its rotation in open and closed positions of the switch.

2. An electric switch as set forth in claim 1, wherein the ends of the slot in the housing top provide the stops for the wheel lever in both directions.

10 3. An electric switch as set forth in claim 1, wherein the wheel is shaped with a peripheral groove and the movable contact means are attached inside the groove.

4. An electric switch as set forth in claim 1, wherein the housing top is further provided with at least one leaf spring 15 pressing on the rim of the wheel; and wherein said rim is made wider where a halt under the leaf spring is intended to raise friction there.

5. An electric switch as set forth in claim 1, wherein a spring loaded stop bolt is further provided projecting from a flat 20 wheel face; and a cavity in an opposite wall of the housing is adapted to receive the bolt.

6. An electric switch as set forth in claim 1, wherein the housing top is formed into a bracket with spaced ledges and aligned holes in the ledges; and wherein the wheel is provided 25 in its center with a transverse shaft that is mounted in said holes for rotation.

7. An electric switch as set forth in claim 1, wherein the eccentric trunnion is mounted between the center and the top of the wheel.

30 8. An electric switch as set forth in claim 1, wherein the eccentric trunnion is mounted between the center and the bottom of the wheel.

9. An electric switch as set forth in claim 1, wherein the housing base contains two pairs of stationary contacts and 35 wherein room for a jumper is provided to tie the neighboring contacts of each pair completing two parallel circuits to be switched alternatively.

10. An electric switch as set forth in claim 1, wherein the stationary contacts are formed into terminals at both ends to allow parallel circuits to be connected.
